UNITED STATES PATENT OFFICE.

THOMAS J. LITTLE, OF PHILADELPHIA, PENNSYLVANIA.

INKSTAND.

SPECIFICATION forming part of Letters Patent No. 326,044, dated September 8, 1885.

Application filed March 31, 1885. (No model.)

To all whom it may concern:

Be it known that I, THOMAS J. LITTLE, a citizen of the United States, and a resident of Philadelphia, Pennsylvania, have invented 5 certain Improvements in Inkstands, of which the following is a specification.

The object of my invention is to construct a cheap and simple inkstand which can be very readily kept clean and easily filled; and 10 this object I attain by constructing the inkstand as hereinafter fully described and claimed.

In the accompanying drawings, Figure 1 is a vertical section of one form of my improved 15 inkstand. Fig. 2 is a sectional view of a modification. Fig. 3 is a plan view of the same with the cover removed, and Fig. 4 is a perspective view, illustrating the two parts detached from each other, of the simplest form 20 of my improved inkstand.

I prefer to make the inkstand entirely of 25 glass, and the body A may be of the general rectangular form illustrated in Fig. 1, or of the octagonal form illustrated in Fig. 3, or of the cubical or other suitable design illustrated in Fig. 4.

I form the well a for the ink in the body or block A, and make the well with a rounded bottom, as illustrated in Figs. 1, 2, and 4, 30 while the top a' is formed perfectly flat, without flange or rib, so that there will be no crevice into which the ink may collect to interfere with the easy cleaning of the stand.

If desired, the glass body of the stand may 35 have molded in it at the same time a recess, B, for the reception of a pen, brush, or sponge, D, as shown in the modification, Fig. 1; but this forms no essential part of my invention.

In order to prevent the evaporation of ink 40 from the well of the stand, I provide the latter with a hopper or funnel-shaped cover, E, with a central opening for the dipping of the pen. I make the rim F of this cover with per-

fectly flat under side f, which can rest on the flat surface a' of the top of the body of 45 the inkstand, and form a good joint therewith. When in use, the joint is closed still more by the creeping up of the ink on the sides of the well, with the result of gumming the cover into place and forming a tight joint, 50 so that when it is desired to remove this cover E to clean the inkstand it will be necessary to use a little force.

The rim F of the cover E is provided on its inner upper side with a rib or flange, e, 55 which performs a double function.

In connection with the hopper-shaped cover E, a small ball, G, may be used, as shown in Fig. 1, to automatically close the central opening after each dip of the pen, and this rib or 60 flange e will prevent the jumping out of the ball when the pen is quickly dipped into the ink, while, on the other hand, the rib or flange e, forms a convenient seat for the removable lid H, Fig. 2, when it is desired to use such 65 in place of or in connection with the self-closing stopper G.

I prefer to form on the upper surface of the rim F of the cover a series of protuberances, f', which form recesses for holding the pen 70 when the latter is laid across the top of the cover.

I claim as my invention—

An inkstand having a well and a flat top, in combination with a hopper-shaped cover 75 adapted to receive an automatic ball-stopper, and having a flat under side, f, and a flange, e, around its inner upper edge, substantially as and for the purpose described.

In testimony whereof I have signed my 80 name to this specification in the presence of two subscribing witnesses.

THOMAS J. LITTLE.
